UNITED STATES PATENT OFFICE.

WILLIAM H. ALBACH, OF MOUNT GILEAD, OHIO.

FOOT-PLASTER.

SPECIFICATION forming part of Letters Patent No. 793,975, dated July 4, 1905.

Application filed February 18, 1905. Serial No. 246,227.

To all whom it may concern:

Be it known that I, WILLIAM H. ALBACH, a citizen of the United States, residing at Mount Gilead, in the county of Morrow and State of Ohio, have invented certain new and useful Improvements in Foot-Plasters, of which the following is a specification.

My invention relates to porous plasters, and has particular relation to plasters adapted to be used on the bottom or sole of the foot.

The objects of my invention are to provide an improved plaster adapted to be secured to the under surface of the foot, the said plaster having substantially the form or outline of the ball and forward portion of the foot, and to provide in conjunction therewith means for securing the plaster in connection with the under side of the foot and to produce other improvements the details of which will be more fully pointed out hereinafter.

With the above and other objects in view the invention consists of the novel details of construction and operation, a preferable embodiment of which is described in the specification and illustrated in the accompanying drawings, wherein—

Figure 1 is a bottom view of a human foot, showing one of my plasters applied thereto. Fig. 2 is a plan view of the plaster; and Fig. 3 is a transverse sectional view of the plaster, taken on the line $\pi\pi$ of Fig. 2.

In the drawings the numeral 1 designates the plaster, which is formed with the enlarged or bulged forward portion 2, adapted to conform generally to the ball of the foot and merging rearwardly into the contracted portion 3, adapted to substantially fit the forward portion of the arch of the foot. The plaster is of the porous type, comprising a fabric body, on one face of which is applied in the usual manner a suitable plastic medicinal preparation 5, which lies next to the foot when the plaster is applied. Perforations 7 are made through the fabric, so as to supply air and prevent the foot from perspiring.

For securing the plaster to the foot I preferably provide upon each side tabs 8 and 9, two on each side and the forward tabs 8 well

to the front of the plaster, so as to engage with the foot in front of its natural projections a and b at the ball. The rear tabs 9 are positioned so as to engage the foot to the rear of the said projections a and b . By such an arrangement and disposition the plaster is firmly secured in place and prevented from creeping or becoming dislodged, it being understood that the upper surfaces of the tabs 8 and 9 are coated with a suitable adhesive, by which the said tabs may be attached to the foot. If found desirable, the plaster-body may be extended laterally to permit of such extensions when provided with suitable adhesive substance being turned up against the sides of the foot and utilized as a further or additional means of attachment. By turning up the tabs and engaging them with the sides of the foot a practical and superior fastening is had, as the sides of the foot are free from moisture due to perspiration, and they are thus caused to adhere to dry skin, it being understood that the plaster could not be securely held to the bottom or sole of the foot, as the same is at all times more or less moist or damp.

Much stress is to be laid on the general shape of the plaster and to the portion of the foot to which it is applied, as the plaster not only stimulates the action of the blood in the foot and relieves soreness and ache, but acts as a cushion, thus adding to the ease and comfort of the wearer. It is to be further observed that by shaping the plaster in the manner which I have set forth and described the foot is allowed a free and natural action and that the plaster is applied directly to the parts most liable to be affected and in no way interferes with the apparel of the wearer.

It will be noted that the attaching-tabs of opposite sides of the plaster are arranged in diagonal and horizontal alinement, this opposing arrangement being such as to insure the plaster fabric being drawn taut across the bottom of the foot and preventing undesirable wrinkling of the material.

I do not wish to limit myself to the exact details of construction and operation herein set forth, as I may make various changes in

the same wholly within the scope of my claims and without departing from the spirit of my invention.

Having now fully described my invention, 5 what I claim, and desire to secure by Letters Patent, is—

A medicinal foot-plaster shaped to fit the forward portion of the bottom of a human foot and cover the ball thereof, and tabs formed

with the plaster so as to be engaged with the 10 foot forwardly and rearwardly of the natural projections adjacent the ball of the foot.

In testimony whereof I affix my signature in presence of two witnesses.

WILLIAM H. ALBACH.
